UNITED STATES PATENT OFFICE.

AMOS HARRISON, OF CHICAGO, ILLINOIS, ASSIGNOR TO WARREN WEBSTER & COMPANY, OF CAMDEN, NEW JERSEY, A CORPORATION OF NEW JERSEY.

WATER AND AIR RELIEF-VALVE.

No. 895,265.

Specification of Letters Patent.

Patented Aug. 4, 1908.

Application filed January 26, 1903. Serial No. 140,505.

To all whom it may concern:

Be it known that I, AMOS HARRISON, a citizen of the United States, residing at Chicago, in the county of Cook and State of Illinois, have invented certain new and useful Improvements in Water and Air Relief-Valves, of which the following is a description.

My improved valve is intended to control the discharge of air and water of condensation from a radiator outlet, or the like, and is particularly adapted for use in those steam heating systems in which a lower pressure is maintained in the return.

In such systems, when the thoroughfare is opened by the lifting of the valve piece, the water of condensation is drawn out by the lower pressure in the return, and if the thoroughfare remains open after the water has passed out, steam will be drawn out also and there will be a loss of heat units. It is therefore desirable that the thoroughfare should be open at those times only when water of condensation is present in material volume. It has been proposed for this purpose to use a float valve, *i. e.* a valve-piece carried by a float which is lifted by the water of condensation to open the thoroughfare and falls when the water has escaped. In such valves, however, when used in "vacuum systems", the suction or lower pressure in the return acts against the flotation and tends to hold the valve closed. A simple float valve of this character is also objectionable because it affords no provision for the escape of air while the valve is closed, and, in vacuum systems, the constant free discharge of air is necessary to successful operation. It has also been proposed to actuate

the valve by a fluid pressure motor operated by the difference in the pressures on the inlet and outlet sides of the valve body, under the control of the conditions, such as the presence of water of condensation, on the inlet side. In such cases, when the valve piece is closed, the air is drawn out through an air passageway, which is sealed by the accumulation of water on the inlet side, either directly, or by the operation of mechanical devices, such as a float, and when this passageway is thus sealed, the differential is produced on the pressure motor and the valve piece is opened. In such valves, however, the water of condensation acts merely to seal the air passageway, and the operation of

the valve piece is produced wholly by the differential pressure acting on the motor. It is therefore necessary at all times to maintain conditions capable of producing a sufficiently great differential to operate the motor.

It is the object of my invention to combine in one valve structure the advantages of both the float and pressure motor types, and to this end I control the valve piece by a motor-float, or a device which acts both as a float and as a pressure motor, and is so arranged that the accumulation of water of condensation, which acts to lift the motor-float by flotation, also acts to seal the air passageway and produce the differential pressure. The two forces of flotation and unbalanced pressure are thus acting simultaneously in aid of one another. It results that a smaller differential pressure can be used to actuate the valve, resulting in more economical conditions of operation, and a heavier and stronger float-motor may be employed.

In the drawings: Figure 1 is a vertical section of my air and water relief valve illustrating one form or type; Fig. 2 is a horizontal section on the line 2—2 of Fig. 1; Fig. 3 is an enlarged view of part of Fig. 1; Fig. 4 is a horizontal section on the line 4—4 of Fig. 3; Fig. 4² is a side elevation of a steam radiator and its supply and return connections illustrating the location of the valve; Fig. 5 is a vertical section similar to Fig. 1 illustrating a second form or type; and Fig. 6 is a horizontal section on the line 6—6 of Fig. 5.

The valve body 1 may be of any usual form having an inlet 2 and an outlet 3. It is shown open at the top and provided with a removable screw threaded cap 4.

8 is the motor-float within the valve-body which carries the valve-piece 9 adapted to control the thoroughfare to the outlet. In the construction shown in Figs. 1 and 2 this motor-float is open at the top and is guided in its movements on a rod 10 fastened at the top in the cap 4 and held at the bottom in a support 12 in the outlet, the body 8 being provided with a guide spider 11. The hole in the neck of the motor-float and its valve piece 9, through which the rod passes, is of somewhat larger diameter than the rod, to afford an air passageway 30.

The diameter of the body 8 of the motor-float is such that its outer surfaces are close to the inner walls of the valve-body, or to a wall therein, to form a normal air space to

the top of the motor-float, but adapted, when a material volume of water of condensation collects in the valve-body, to be sealed by said water.

5 In the construction shown in Figs. 1 and 2 the valve body is shown provided on one side with a depending wall or partition 5 extending nearly to the bottom of the valve-body, with the motor-float arranged within said 10 wall and the opposite side wall of the valve-body. In the upper part of this partition may be placed an air vent controlled by an adjustable plug 6.

The operation is as follows: In the absence 15 of a material quantity of water of condensation, the motor-float is in its lowest position with the valve-piece closed on its seat as shown in Fig. 1. At such times the air entering through the inlet 2 passes under the 20 partition 5 and up to the interior of the float and thence through the passageway 30 to the outlet. A portion of the air may also pass through the plug 6, but that is not material. At such times the air will pass out freely and 25 there will be no operation of the motor-float. When, however, water of condensation accumulates in the valve-body in sufficient 30 quantity to act upon the bottom of the motor-float and float it, the water will at the same time pass up into the air space between the outer wall of the motor-float and the 35 valve-body or partition 5 and seal it. As the free air passageway will then be closed (except for the plug controlled vent 6, which, 40 however, is too small to affect the result) a lower pressure will be created on the inner side of the motor-float, which will co-act with the lifting action of the water to raise the motor-float and open the valve. As this 45 movement is produced by the combined action of the differential pressure acting on the motor-float and flotation, it may be obtained with much less differential than would otherwise be necessary, thus requiring less partial 50 vacuum in the returns and a more economical condition of operation. It also enables a heavier and more durable float to be used. If the upper edge of the open float seated against the top of the cap, as would occur in 55 such a construction as is shown in Fig. 1, it might happen that the lower pressure or partial vacuum created in the body of the motor-float might prevent it from falling when the water passed out. To prevent this a small vent 13 may be placed in the upper 60 part of the motor float and the vent 6 may be employed in the wall 5.

In the construction shown in Figs. 5 and 6, instead of the partition wall 5 on one side, 65 there is shown a dome shaped wall 14 carried by the cap 4 and fitting over the motor-float. This dome shaped wall may be provided with a vent 15 controlled by a plug 16 to relieve the suction in the motor-float after it 70 has seated on the inside of the dome wall.

This water and air relief valve, while adapted especially to "vacuum systems" of steam heating, may also be used in pressure systems, as the motor-float will operate in the manner described in any system in which 70 there is a differential in the pressure in the inlet and outlet of the valve body, whether that differential be produced by the removal of air from the returns by suction creating devices, or by the drop in pressure due to the 75 physical conditions of operation.

What I claim as new and desire to secure by Letters Patent is as follows:

1. Valve mechanism for discharging air and water of condensation from steam heating systems, consisting of a valve-body having an inlet and an outlet, a float in said body, a valve-piece carried by said float to control said outlet and having an air discharge passageway through it to the interior of the 80 float, and a wall arranged between the inlet and float and having an opening at the top for the discharge of air the interior of the float communicating with the space within the wall about said float and said space also 85 communicating under said wall with the inlet.

2. Valve mechanism for discharging air and water of condensation from steam heating systems, consisting of a valve-body having an inlet and an outlet, a cylindrical casing within said body, a float within said cylindrical casing, and a valve-piece controlling said outlet and carried by said float and having an air discharge passageway 90 leading through it and forming a communication between the outlet and the upper part of the space within the casing, the space within said casing about the float communicating under said casing with the inlet. 100

3. Valve mechanism for discharging air and water of condensation from steam heating systems, consisting of a valve-body having an inlet and an outlet, a cylindrical casing within said body, a guide rod within the valve-body, a float within said casing guided by said rod, and a valve-piece to control the outlet carried by said float and having an air discharge passageway forming a communication between the outlet and the upper part 110 of the space within the casing, the space within the casing about the float communicating under said casing with the inlet. 115

4. Valve mechanism for discharging air and water of condensation from steam heating systems, consisting of a valve-body having an opening at the top and provided with an inlet and an outlet, a detachable cap closing the opening at the top of said body, a depending guide rod carried by said cap, a 120 float guided by said rod, a valve-piece to control the outlet carried by said float, a depending wall in said body between the inlet and float and having its lower edge 125 below the top of the inlet, said valve-piece 130

having an air discharge passageway forming a communication between the outlet and the upper part of the space inside of said depending wall, and the inner space between said wall and float communicating under the lower edge of said wall with the inlet.

5. Valve mechanism for discharging air and water of condensation from steam heating systems, consisting of a valve-body having an inlet and an outlet, a float in said body, a valve-piece to control said outlet operatively connected with and controlled by said float, and a depending wall between the inlet and float having its lower edge below 10 the top of the inlet, said valve-piece having an air discharge passageway forming a communication between the outlet and the upper part of the space within the depending wall, and the space between said wall and float 15 communicating under the lower edge of said wall with the inlet.

6. Valve mechanism for discharging air and water of condensation from steam heating systems, consisting of a valve-body having a float chamber provided with an outlet for the discharge of water of condensation, a float in said float chamber, a valve-piece to control said outlet operatively connected with and controlled by said float, said valve 20 mechanism being provided with a conduit leading from the inlet to the upper part of the float chamber, and the valve-piece being 25

provided with an air discharge passageway forming a communication between the outlet and the upper part of the float chamber into 30 which the air is discharged through said conduit.

7. Valve mechanism for discharging air and water of condensation from steam heating systems by differential pressure comprising a float chamber provided with an outlet, a float in said chamber, said mechanism having a conduit adapted to provide communication between the radiator and float chamber, a liquid seal arranged to be sealed by the 40 accumulation of water of condensation in said conduit, thereby increasing the differential pressure on opposite sides of said liquid seal, whereby a portion of the accumulated water of condensation is forced into 45 said float chamber, and a valve-piece to control the outlet carried by said float and having an air discharge passageway through it forming a communication between the outlet and the interior of the float, whereby the 50 air which has passed the water seal will be discharged through the float and valve-piece.

In testimony whereof, I have hereunto subscribed my name in the presence of two (2) witnesses.

AMOS HARRISON.
